Frank J. Kowalski and Michael Scavone, Baltimore, Md., assignors to Bethlehem Steel Company, a corporation of Pennsylvania

Filed Sept. 13, 1954, Ser. No. 455,426

4 Claims. (Cl. 182—150)

This invention relates in general to scaffolds or staging, and more particularly to adjustable metal staging for painting, cleaning and similar work on the sideshell plating of ship's hulls.

The objects of this invention include the provision of reliable means for suspending and spacing the staging elements in any desired relation to the side plating of the ship, and safe and rigid platform means adapted for use with one or more of said staging elements.

Other objects, purposes and advantages of the invention will appear hereinafter in the specification, and in the claims and drawings forming a part hereof.

In the seven (7) sheets of drawings hereto attached:

Figure 1 is a front elevation of the upper and lower sections of the staging;

Fig. 2 is a vertical section taken on the line 2—2 of Fig. 1, with portions of the ship's deck and shell plating also being shown in section;

Fig. 3 is a partially cut-away isometric view of a telescoping strut and a hook hanger for suspending the lower section of the staging from the upper section;

Fig. 4 is an isometric view of a tapered locking key;

Fig. 5 is an isometric view of a top section hanger and chain suspended platform;

Fig. 6 is a bottom plan view of one of the telescopic members supporting said platform;

Fig. 7 is a vertical section of said telescopic member, on the line 7—7 of Fig. 6;

Fig. 8 is a vertical section on the line 8—8 of Fig. 10, showing the lattice bracing and lifting pin;

Fig. 9 is a detail view of the slotted lower pipe of one top section hanger prior to welding to the top of the adjacent vertical channel;

Fig. 10 is a top plan view of the staging, partly in section, and showing the lattice bracing connecting the top section hangers and the manner of folding said hangers inward for storage;

Fig. 11 is a detail view of the inner side of one top section hanger;

Fig. 12 is a vertical section of said top section hanger on the line 12—12 of Fig. 11;

Fig. 13 is a front detail view of said top section hanger;

Fig. 14 is a horizontal section on the line 14—14 of Fig. 1, viewing downward to the platform;

Fig. 15 is a section on the line 15—15 of Fig. 1, and showing telescopic side struts, ladder, and pipe bracing connecting the vertical channels;

Fig. 16 is a horizontal section on the line 16—16 of Fig. 1, showing a typical spacer rung connecting vertical channels;

Fig. 17 is a section on the line 17—17 of Fig. 14, showing one of the platform staples;

Fig. 18 is a vertical section on the line 18—18 of Fig. 16;

Fig. 19 is a top plan view of an intermediate platform which may be used between spaced staging units;

Fig. 20 is a front elevation of said intermediate plat-

form showing pipe stanchions supporting chains for safety rails;

Fig. 21 is a vertical section on the line 21—21 of Fig. 20;

5 Fig. 22 is an enlarged view of one of the platform staples of Fig. 19;

Fig. 23 is an enlarged isometric view of the bottom end of a pipe stanchion with locating pin in place in bayonet slot of pipe socket;

10 Fig. 24 is a broken front elevation showing the manner in which an intermediate platform may be supported by the platforms of adjacent staging units; and

Fig. 25 is a side view of a portable ladder supported on one of the rungs of the staging ladder and providing convenient access to the deck of the ship.

Referring now to the numerals designating individual parts, the staging in its most general aspect is comprised of a top panel section 1 of braced upright members suspended from the deck 2 and gunwale 3 of a ship

20 by a rearwardly foldable top section hanger 4, a bottom panel section 5 of welded members similar to the top panel section and suspended therefrom by hook members 6, extensible horizontal pipe struts 7 adjustable to

25 the inward slope of the ship's side plating 8, and a vertically movable platform 9 with box-shaped extension members 11.

The upright members at each side of the top panel section 1 consists of pairs of parallel vertical channels 12 perforated at regular intervals to receive long rivets 13 welded thereto as at 14 and 15 to serve as rung spacers connecting said channels 12 with their rear faces in evenly spaced relation as shown in Figs. 16 and 18.

Said upright side members are formed into rigid open panels by horizontal braces of round bars 16 and section 35 heavy pipes 17 and X-braces 18 likewise of heavy pipes welded at properly spaced intervals to the front or flanged faces of opposite vertical channels 12. Additional strength at the top to permit lifting by cranes or the like is provided by a pair of horizontal parallel

40 channels 19 welded between the uprights and spaced apart by diagonal flat bars 21 welded in crosswise relation on top and bottom to form a lattice, also having a pair of round bars 22 welded between said channels 19 at suitable intervals to engage a pair of lifting hooks (not shown). A lower upright pipe brace 23 and a fixed ladder 24 of round bar rungs 25 welded between flat bar stringers 26 as shown in Fig. 1 also add to rigidity, in addition to the ordinary uses of the ladder.

Each pair of vertical channels 12 is surmounted by 50 an upwardly extending pipe 27 having a plurality of longitudinal slots 28 as in Fig. 9 whereby the lower end of said pipe 27 engages similar slots in the webs 29 at the top of said channels 12 and is welded thereto. Each of said pipes 27 is encircled by a welded band 31, 55 and has a round cap plate 32 with a central opening 33 in which a large upright stud 34 is welded with its threaded end 35 at top.

For hinging the top section hanger, a larger pipe 36 with a grease fitting 37 rotatably surrounds each of the 60 first-mentioned pipes 27, and supports the parallel horizontal channels 38 and the top plate members 39 and 41 of the hanger assembly welded thereto. A washer 42, hex nut 43, and cotter pin 44 secure the hanger assembly to the threaded end 35 of the stud 34. At the 65 opposite end of the parallel horizontal channels and welded therebetween is an inverted U-shaped plate 45, braced by a welded plate bracket 46 and having its depending outer end provided on both sides with inwardly extending bolted angles 47 for engaging the deck 2 and gunwale 3 of the ship.

Stop blocks 48 and 49 welded to each lower pipe 27 are adapted to engage a lug 51 on the upper pipe 36.

and restrict the hanger assembly to fold in and out not exceeding 90° as shown in Fig. 10, and together with said lugs 51 are provided with bolt-holes 52 to permit securing the top section hanger 4 in either open or closed position.

A top panel section 1 as described above may be of any desired dimensions, but a top panel section 18 feet high and 20 feet wide has been found to meet most ordinary requirements, either alone or, if necessary, supplemented by a lower panel section 5 of the same width and about 12 feet high.

For suspending the lower panel section 5 from the top panel section 1, the large downwardly extending hook 6 is welded between the bottom ends of the vertical channels 12 of said top panel section.

Said lower panel section 5 is generally similar to the top panel section 1, as above described, but the bowed upper portions 53 of the vertical channels constituting the side members of said lower panel section 5 are more widely spread apart than the straight lower portions 54, and are provided with a heavy lifting pin 55 welded therebetween to engage the suspension hook 6. Said hook 6 is secured in place by a tapered locking key 56 attached by chain 57 to an adjacent member and inserted in registering holes 58 through said channels 53 and the hook 6 and fastened by a cotter pin 59. Offset auxiliary upper side channels 61 and the lower straight channel portion 54 are provided with welded spacing rung members 62 for platform support. Face plates 63 and 64 at top and bottom and bracket 65, under the auxiliary channel 61 additionally strengthen each channel assembly.

The upright members on opposite sides of the bottom panel 5 are joined in spaced relation by transverse pipe braces 66, 67, 68 and 69, the middle pipe brace 67 being welded with X-bracing pipes 71 to a central plate bracket 72.

In other respects, including the ladder 73 and the top channels 74 and associated lifting bars 75 and lattice bars 76, the structures of the bottom panel 5 and the top panel 1 are essentially the same.

Adjacent the lower ends of each of the top and bottom panel sections, there is welded to the inside flanges 77 of the vertical side channels a pad 78, having a pair of parallel vertically disposed brackets 79 welded thereon. Said brackets hold a vertically disposed rounded plate 81 with a nut 82 securing a pivot bolt 83 in registering holes therethrough to permit service as a hinge. An inwardly projecting lower portion (not shown) of said plate 81 is adapted to engage the pad 78 and prevent the slotted pipe 84 welded on the other end of the plate from being lowered below a horizontal plane.

Telescopically movable within said pipe 84 is a smaller pipe 85 terminating in a welded round cap plate 86 adapted to engage the side shell plating 8 of the ship when the strut is extended. Bolts (not shown) through registering apertures 87 in the pipes 84 and 85 will hold the struts in the desired position.

Mounted on one of the spacer rungs 13 or 62 at the desired working level is the inner hook portion 88 of the platform hanger casting 89, having side flanges 91 engaging the adjacent flanges 77 of the vertical side channels 12, and a projecting lug 92 in which a pivot bolt 93 secured by a nut 94 permits upwardly hinging movement of the side plate 95 supporting the staging platform 9. Said platform 9 comprises a pair of spaced channels 96 and 97 extending longitudinally of the panel and connected by end channels 98, adjacent parallel channels 99, and diagonal and transverse braces 101, 102 and 103 of welded angles. A longitudinally disposed angle 104 somewhat shorter than the adjacent longitudinal channel 96 is connected thereto by welded end brackets 105 and inner brackets 106, and provides additional support for the platform flooring of expanded

metal mesh 107 or the like. At each end of the longitudinal channel 97 located at furthest distance from the plane of the vertical channels 12 is welded an upwardly extending end plate 108 to which the lower end of a suspension chain 109 is pivotally secured by a shackle 111 and pin 112. The upper end of said chain 109 is secured by shackle 113 and pin 114 to a hook 115 engaging one of the spacer rungs 13 or 62 a few feet above the platform level. A U-shaped staple 116 and welded bottom closure plate 117 as in Fig. 17 assist in lifting the platform 9 when required.

Welded beneath each of the channels 99 is a rectangular tubular member 118 having an elongated longitudinal slot 119 in its bottom surface 121 (Fig. 6) in which 15 a projecting rivet stop member 122 welded as at 123 to inner rectangular tubular member 124 (Fig. 7) having a cap plate 125 permits a limited range of telescopic extension of said inner tubular member 124 to provide support for such additional flooring (not shown) as may 20 be needed.

Where two or more staging units are to be used, they may be utilized to maximum advantage by placing them in spaced relation and supporting an intermediate platform 126 on the ends of the staging platforms 9 of the 25 spaced units, as best shown in Fig. 24.

Said intermediate platform 126 may likewise have expanded metal mesh flooring 127 on a rectangular frame of welded front and rear angles 128 and 129, with angle stiffeners 131 and center brace 132 and a depending central angle 133 having a pipe collar 134 through which extends a longitudinal brace rod 135 having its threaded ends 136 secured by nuts 137 to brackets 138 beneath the front edge angle 128.

Said front edge angle 128 has mounted thereon a 35 plurality of pipe sockets 139, each with a bayonet slot 141 to engage a locating pin or rivet 142 welded near the bottom of a pipe stanchion 143 having a cap plate 144 and bar loops 145 for a safety chain 146. A staple 147 and bottom plate 148 (Fig. 22) in the center angle brace 40 132 allows easy lifting of this platform.

A portable metal ladder 149 (Fig. 25) with round bar rungs 151 and stringers 152 slotted at their bottom ends as at 153 to engage rungs 25 on the fixed ladder 24 will 45 provide convenient access to and from the deck 2 for workmen using the staging.

It will be observed that the suspended staging device which is the subject matter of this invention is especially suitable for use on ships of virtually any type or size, yet it may be adapted for use on elevated structures of 50 other kinds without important changes. It is also very quickly and easily set up or moved or taken down, and folds very compactly for convenient storage when not in use.

Although the invention has been described hereinabove 55 in considerable detail, it is not desired to have it limited to the exact and specific particulars stated, but there may also be used such substitutes, modifications or equivalents thereof as are included within the scope and spirit of the invention or pointed out in the appended claims.

60 We claim:

1. A suspension scaffold for ships comprising a pair of uprights, each upright comprising a pair of parallel vertical structural channels in back to back spaced relation, a plurality of horizontal spacer rungs secured at regular 65 intervals between each pair of channels, a hanger member on the upper end of each upright, a pair of horizontally spaced parallel channels in back to back relation connecting the upper portions of the uprights, a plurality of criss-cross braces connecting the last-mentioned channels, and transverse braces connecting the lower portions of the uprights.

2. In a suspension scaffold as claimed in claim 1, each 70 hanger member comprising an upwardly extending tubular member affixed to the top of each upright, an outer sleeve rotatably mounted on said tubular member, a

straight laterally swinging arm of paired structural channels attached at one end to the top of said sleeve, an inverted U-shaped plate member integrally attached on the opposite end of said arms, and means for securing said arm in open or folded position as desired.

5

3. In a suspension scaffold as claimed in claim 1, the combination therewith of detachable hinge means including hook portions engaging certain of the aforesaid rungs, a rectangular framework of structural channels comprising a platform secured to said hinge means, expanded metal flooring on said platform, hooks gripping other rungs above the hinge means, and means connecting said latter hooks to the outer edge of the platform to suspend said platform in horizontal position.

4. In a suspension scaffold, a pair of uprights, each 15 upright comprising a pair of vertical, spaced, parallel structural channels, a plurality of rungs secured at intervals between each pair of channels, a vertically pivoted arm secured to the upper end of each upright for suspending the uprights spaced from a wall, bracing connecting said uprights, a working platform extending between said uprights and said wall and having two longitudinal sides, hooks on one side of said platform engaging a rung in each of said uprights, and braces on the other side of said platform engaging a rung in each of said 20 uprights vertically spaced from the first-mentioned rungs.
